PROCESS OF TREATING WOOD

Charles F. Preston, Sr., Harrison, N. Y., assignor,
by direct and mesne assignments, to Lignose,
Inc., Mamaroneck, N. Y., a corporation of
New York

No Drawing. Application January 24, 1936,
Serial No. 60,710

2 Claims. (Cl. 91—70)

The present invention relates to a process of treating wood, and more particularly to a process by which various of the so-called soft and relatively inexpensive woods, such as pine and other soft woods, so treated that its surface will be made to resemble in appearance the harder and relatively expensive woods, such as mahogany, walnut, rosewood, teak, and the like.

The object of the invention is to so treat the surface of wood having a natural grain, that the fats or gums forming the grain will not only be impregnated with a dye or stain fused therein but will also be hardened, while at the same time removing a portion of the treated surface to a greater or less degree during the finishing operation, thus producing a finished surface in which the natural grain is emphasized in contrast with the adjacent surface composed of soft and spongy fibers, thereby producing a highly ornamental surface closely imitating the appearance of the harder and more expensive woods.

With the foregoing object in view, my invention may be said to consist of a process of finishing the surface of wood by applying thereto a dye or stain containing a mild form of acid which acts upon and softens the exposed surface of the grain fats or gums and immediately thereafter subjecting the surface to the action of heat of a temperature sufficient to dry the surface and to soften the grain fats and gums and cause the dye or stain to be absorbed thereby and fixed therein in the exposed surface thereof.

In carrying out my invention the dye or stain or fusing compound will be applied to the surface to be treated. This dye or stain will preferably be one containing any usual form of coal tar coloring such as an aniline dye. Before applying it to the surface of the wood there will be added thereto a small amount of vinegar or other form of mild acid, and in some instances a small amount of sugar. When applied to the surface of the wood the dye or stain will be absorbed to a considerable degree, and wherever the fatty grain gum is exposed it will to a certain extent be softened permitting the dye to be absorbed thereby. Immediately after applying the dye or stain compound to the surface to be treated, it is subjected to heat applied directly thereto by any suitable heating means as, for instance, by a torch passed rapidly over the surface or closely adjacent thereto. The heat treatment should not be continued long enough to produce a scorching effect, but only to that extent required to dry the surface and to soften the grain fats or gums and blend the coloring therewith. After heating and drying, the grain fats or gums will become relatively hard with the result that the dye or color is permanently incorporated therein.

60 I next treat the surface with any suitable abrad-

ing tool as, for instance, a wire brush, to remove a portion thereof, and as the fatty grains and gums are much harder than the adjacent soft and spongy fibers, this abrasive treatment will effect a polishing of the surface thereof bringing out the color or tint, producing a contrasting shade of the natural grain with the adjacent soft fibers. This abrasive treatment will be continued until sufficient of the surface has been removed to produce the desired color tone and the harmonious blending of the darker shades of color in the natural grain with the contrasting lighter shades in the adjacent softer fibers.

Thereafter if desired, and to produce a highly polished surface, it is subjected to a waxing and polishing brush in the usual manner. The wax employed may be one having a color blended therewith, and this waxing and polishing operation may be continued indefinitely or until the surface has the desired finish.

Before subjecting the surface to the waxing and polishing operation, if a harmonious blending of tone is desired, such as that known as gray-green or other blended tone, this may be applied so that it will be taken up by the soft and spongy fibers adjacent the hard, fatty, grain surface.

It may be pointed out that the heat treatment immediately following the application of the dyeing or coloring liquid compound softens the naturally fatty gums of the wood and fixes the color therein by producing a liquid steam action, and that after the heat treatment the fatty grains when dry become much harder which, under the action of the wire brush and subsequent finishing, present a highly polished surface.

I claim:

1. The method of finishing the surface of wood having a natural fatty grain exposed thereon, which comprises the following: applying a stain containing a mild acid to the said surface, subjecting the stained surface to heat of a temperature to soften the exposed fat or gum forming the natural fatty grain to impregnate and fix the stain therein and thereafter abrading the stained surface to remove a portion of the softer spongy surface to emphasize the natural fatty grain.

2. The method of finishing the surface of wood having a natural fatty grain exposed thereon, which comprises the following: applying a stain containing a weak solution of acetic acid to the said surface, subjecting the stained surface to heat of a temperature to soften the exposed fat or gum forming the natural grain to impregnate and fix the stain therein and thereafter abrading the stained surface to remove a portion thereof, and finally waxing and polishing the surface.

CHARLES F. PRESTON, Sr. 60
